UNITED STATES PATENT OFFICE.

JOHN LAWSON, OF CENTRAL FALLS, RHODE ISLAND.

DROP-STITCH KNITTING-MACHINE.

1,140,270.

Specification of Letters Patent. Patented May 18, 1915.

Application filed November 8, 1911. Serial No. 659,117.

To all whom it may concern:

Be it known that I, JOHN LAWSON, a citizen of the United States, residing at Central Falls, in the county of Providence and State of Rhode Island, have invented 5 certain new and useful Improvements in Drop-Stitch Knitting-Machines, of which the following is a specification.

This invention relates to automatic circular knitting machines of the class more especially adapted for knitting drop-stitch hosiery.

The object of the invention is to provide a circular knitting-machine of the rotary needle-cylinder type with means for producing automatically what may be termed an "all round drop-stitch stocking," that is, a stocking having its entire leg portion or tubular part provided throughout its circumference with a plurality of connected, suitably spaced series or groups of both plain and drop stitches, alternating with each other, each of said series consisting of a number of longitudinal rows of plain 20 stitches and one or more rows of drop-stitches; the latter corresponding with the number of the then inactive or omitted needles, and having the knitting produced in a continuous circular manner 25 from the main thread by the use of plain or ordinary latch needles. The rows of said plain and drop stitches thus formed in the back of the leg part terminate at or before the commencement of the heel; that is to 30 say, parts of the courses of plain stitches may, if desired, be produced in the back of the leg to form therein what is termed a "high-splice." The rows of plain and drop 35 stitches in the front part of the leg continue downward uninterruptedly throughout the upper part of the foot portion and terminate at the toe part. The said plain heel and toe portions, are or may, if desired, be knitted from a heavier or different 40 kind of thread than the main thread employed in the tubular portions of the stocking. The sole portion, as well as the upper part of the foot, are produced in a continuous circular manner from the main thread; 45 the sole part in such case consists of semi-circular courses of plain stitches, while the top or upper part of the foot consists of semi-circular courses of combined plain and

drop stitches, as before stated. If desired, the foot may have a double sole, that is, a 55 sole produced from different or heavier yarn.

In the present invention and in order to produce in the stocking described longitudinal lines or rows of plain and drop stitches, 60 or open work, certain of the needles are omitted altogether from one-half of the circumference of the needle-cylinder. These vacant needle-grooves correspond with the continuous longitudinal lines of drop- 65 stitches formed in the front of the tubular leg part and also in the upper portion of the foot part of the stocking.

In adapting the machine to produce lines of drop-strokes in the back part of the leg, 70 the corresponding needle-grooves in that half of the cylinder are provided with needles; these latter, however, are temporarily inactive or dropped during the knitting of the back of the leg, and are moved upward 75 into normal knitting position to coöperate with the other needles in the corresponding semi-circumference of the cylinder, so as to be acted upon as usual in producing the heel and toe and also the sole part of the 80 tubular foot. It is obvious, therefore, that the foot portion consists of continuous circular courses of stitches, one-half of each course (the sole part) being knit wholly of plain or ordinary stitches; the other or upper 85 half of each course consisting of a connected series of both plain and drop-strokes.

I am aware that certain types of stocking-knitting machines have been devised for producing lines of drop-strokes in portions 90 of the web.

My present invention relates more especially to means adapted to produce on a full automatic knitting machine of the revolute needle-cylinder type stockings having 95 drop-strokes. My said improvements are comparatively simple and inexpensive, as compared with means employed in other types of circular knitting machines for producing drop-stitch work.

In the five accompanying sheets of drawings, illustrating my invention, Figure 1 represents, in front side elevation, portions of an automatic circular stocking-knitting machine; the position and relation of the 105 devices corresponding to the knitting of the

leg part of a stocking having all-around drop-stitches. Fig. 2 is a corresponding end elevation, in reduced scale, viewed from the left of Fig. 1, some of the parts being omitted. Fig. 3 is a horizontal sectional view, in enlarged scale, taken substantially on line 3-3 of Fig. 1. Fig. 4 is a vertical longitudinal section of the cylinder, &c., taken substantially on line 4-4 of Fig. 3. Figs. 5 and 6 are enlarged partial horizontal sections through the lower portion of the needle-cylinder, showing respectively the extreme outward and inward positions of the jack-cam. Fig. 7 is an enlarged partial front elevation showing the auxiliary needle-deflecting device in action, as at the termination of the stocking. Fig. 8 represents an elevation of the development of a portion of the ring-cam, viewed from its inner face, corresponding with Fig. 1. Fig. 9 is a similar view of the cam-ring, &c., when the cylinder is being reciprocated. Fig. 10 shows the position of the needles and cam-ring while the foot part is being made. Fig. 11 is an enlarged horizontal section showing a portion of the cylinder and the arrangement of the needle-less and needle-carrying grooves; Fig. 12 shows, in enlarged scale, a portion of the web of the leg part of the stocking. Fig. 13 is a partial exterior development, indicating the cylinder and cam-ring and showing the arrangement and position of needles and cams corresponding to the commencement of the top of the leg part of a stocking. Fig. 14 is a similar view showing the relation of the said elements as they would appear in changing from the lower end of the leg part to the beginning of the heel, the short-butt needles then being moved upward into action. Fig. 15 is a similar view showing the long-butt needles being moved upward out of knitting action. Fig. 16 is a vertical section, taken on line 16-16 of Fig. 15, showing short-butt needles deflected into the circular groove communicating with the V-cam; and Fig. 17 represents three types of needles and the two forms of jacks.

It may be stated here that the improvements or devices forming the subject of this application for patent may be adapted to be employed in connection with the circular automatic stocking-knitting machine patented to J. D. Hemphill, September 7, 1909, No. 933,443, to which patent reference may be made. That is to say, in said patented knitting-machine the devices for effecting and controlling the rotary and reciprocatory movements of the needle-cylinder, the yarn changing and feeding means, the main or ring cam and knitting cams, the action of the narrowing and widening pickers, the action of the instep-cam, and means for varying the length of the stitches, all remain substantially the same as though plain knit-

ted stockings were being produced. In the production of fancy or drop-stitch stockings on said machine, or other analogous knitting machines, certain changes or improvements are necessarily introduced. 70 These latter form the basis of this application for patent.

The needle-cylinder *N* is mounted and capable of being actuated both in a revoluble and rotary reciprocatory manner, substantially as in making the usual leg and heel portions of a stocking. In the present invention, however, wherein the machine is adapted to produce all-round drop-stitch stockings, the cylinder is materially lengthened to form an increased space between the lower face of the usual stitch-varying, vertically movable cam-plate *H* and the upper face of the stationary table *a*, positioned below said cam-plate, to receive in certain 80 of the needle-grooves of the cylinder long and short-butt needle-jacks *j* and *j'*, respectively. In this space below the cam-plate is mounted a radially movable jack-cam *m*. The latter, when positioned outward, as 90 shown in Figs. 3, 4, and 5, freely permits the passage of the butts of both forms of jacks between its inner face and the revoluble cylinder, but when partially moved inward to the medium position, cam *m* is engaged only by the long-butt jacks *j*, and when standing in the extreme inward position, the cam surface is capable of being engaged by the butts of all the jacks—see Fig. 6. 100

The needle-cylinder is or may be provided circumferentially throughout with uniformly spaced grooves for the knitting-needles, as usual, but in order to produce longitudinal rows of drop-strokes at certain 105 points in the front half of the leg part of the stocking, some of the needles may be omitted altogether from the corresponding grooves. That is to say, assuming the cylinder to be provided with 220 grooves, forming 22 groups, each comprising 10 grooves, or 11 groups in each semi-circumference, and assuming further that in one-half *x'* of the cylinder, each of its 11 groups consists of 8 grooves having 8 long-butt needles *n* therein and two permanent needleless grooves, *n'*, and having needles mounted in all the grooves of the other half *x* of the cylinder, wherein each of its 11 groups consists of 8 needles having medium-butts *n* 115 and two needles having short-butts *n'*—see Fig. 11. As thus arranged, the web or stocking adapted to be produced on the machine would consist of series or groups of continuous longitudinal rows of alternating 120 plain and drop-strokes *r* and *r'* (Fig. 12) throughout the front half of the leg and upper half of the foot part; it being borne in mind that the long-butt needles *n* are employed only in knitting this half of the 130

stocking. At the same time the medium-butt needles in the other half of the cylinder produce similar rows of plain and drop-strokes in the back half of the leg (the short-butt needles then being temporarily inoperative) down to the commencement of the high-splice (see Fig. 8), or, when the latter is omitted, to the commencement of the heel, at which instant the cylinder is caused to be reciprocating and the short-butt needles normally working in co-operation with the medium-butt needles to knit the heel, as usual, (see Fig. 9). At the completion of the heel, the long-butt needles (temporarily inactive during the knitting of the heel) are returned to the normal knitting plane, the cylinder at the same time being revoluble, to resume circular knitting, thus producing in the upper part of the foot parallel longitudinal rows of plain and drop stitches, as before stated, and also the plain sole or bottom portion. See Fig. 10. During the production of the said sole all the medium and short-butt needles n^1 , n^2 , are meanwhile in normal knitting action. The manner of knitting the toe-pocket is substantially the same as employed in making the heel.

Each pair of individual short-butt needles n^2 of the one-half of the cylinder are located diametrically opposite the corresponding pair of needless grooves n^4 of the other half. In the lower portion of the grooves carrying the respective pairs of short-butt needles are slidably mounted corresponding pairs of needle-jacks, j , j^1 , arranged to engage the said needles n^2 and move them upwardly by means of the automatically positioned radially movable jack-cam m ; the jacks of each pair have butts differing in length. I prefer to arrange the jacks so that the jack j , having the longer butt, of each pair, is positioned in advance of the shorter one, relatively to the normal circular movement of the needle-cylinder, so that the depressed jacks j will first engage the cam m (then in its mid position) and move the corresponding short-butt needles upward into normal knitting position and action while the cylinder N makes one revolution; the next succeeding revolution of the machine placing the cam m in the full inward position so that the other depressed companion jacks j^1 will next engage cam m and successively move the companion needles n^2 upward into normal knitting position and action also. The reason for moving the forward jack and needle of each pair upward immediately in advance of the respective companion jacks j^1 and needles n^2 is that it produces in the web a smoother and neater appearance at the juncture line or point where solid or close knitting is resumed.

The means illustrated for controlling the movements of the jack-cam m comprise a disk-like cam c secured to the left end of the

intermittingly movable main drum or pattern shaft s^1 , a tiltingly mounted horizontal lever d having its front end in continuous yielding engagement with the periphery of disk-cam c , a connection d^1 jointed to the rear end of the lever and to an arm of a movable bell-crank lever d^2 ; the other arm of the latter being in turn jointed to a horizontal link d^3 whose front end is jointed to a bent fulcrumed lever d^4 , having its other end operatively connected to the foot or base m^1 of the vertical A-shaped cam m radially movable in the table a^2 . See Figs. 2, 3, and 4. The engagement of lever d with the cam surfaces or lugs c^1 , c^3 , c^2 places the cam m in the outward, mid and inward positions, respectively, with respect to the outer face of the lower portion of the needle-cylinder. A spring d^5 (Fig. 3) is employed to insure the engagement of the lever with the cam-lugs. The long-butt jacks j (assuming the needle-cylinder to be normally rotating) are adapted to first successively engage the inclined edge of cam m when the latter is in the mid-position, as before stated, thereby moving upward into action the corresponding short-butt needles of each pair. Coincidently with the next turn of the cylinder N the cam m is automatically moved to the full inward position, whereby the short-butt jacks j^1 engage the cam to move upward the other or companion short-butt needles into the knitting plane—see Fig. 6. Obviously, when the cam m is in the extreme outward position the short-butt needles, upon being depressed below the normal casting-off point, act at the same time to depress all the jacks, the butt portions of the latter then freely moving circularly in the space lying between the adjacent faces of the cylinder and cam, as clearly shown, in Fig. 5.

The long-butt needles are adapted to be moved into and out of the normal knitting plane, substantially as shown and described in the patent before referred to. In the present machine, however, some of the needle-grooves in one-half of the circumference of the cylinder (as at n^4 , Fig. 11) are needless, whereby the machine is adapted to positively produce drop-stitch work in the web at points where the needles are thus omitted. The drawing represents said half of the cylinder as having 11 groups, each group comprising 8 needles and 2 vacant grooves: In knitting the heel and toe parts, the cylinder then having a reciprocatory motion, the act of moving the usual gear-clutch b from the quick-speed side to the slow-speed side, causes the horizontal link b^3 , jointed to the upper end of clutch-lever b^1 and to an arm of the bell-crank lever e , to move the vertically guided instep-cam F upward, since the latter is jointed to the other arm of said lever e , thereby correspondingly moving all the long-butt needles

upward out of knitting action. While the cylinder is thus reciprocating, all the medium-butt and short-butt needles, in cooperation with narrowing and widening pickers, are in action to produce the heel part. Upon the completion of the latter, and at the time of shifting the clutch-back to resume quick-speed continuous rotary movement of the cylinder, the long-butt needles n are dropped to the normal level, that is to the upper edge of the cam-ring M secured to the upper face of cam-plate H (see Figs. 7 and 10). The machine now is adapted to produce the foot part of a stocking, in which the upper portion will consist of alternate groups of longitudinal rows of plain and drop stitches, and the lower or sole part of plain or ordinary stitches. During the latter operation the medium-butt 20 and short-butt needles are in continuous knitting action; the jack-cam being still in the outward position.

After completing the toe part and in order to produce a few terminal or looper 25 courses corresponding to all-round drop-stitch work, similar to that formed in the front and back of the leg part, all the needles are deflected downward by the then angularly tipped cam member h , that is, the 30 several needle butts are caused to engage the under side of cam h and are guided to the inclined sides of a suitably disposed V-shaped or cam opening a formed in the wall of the circular ring M , and having the 35 bottom of said opening extending to or below the plane of the casting-off point of the knitting or stitch-cams. The inner face of the relatively stationary ring-cam M is provided with a horizontal, shallow circular 40 groove a^1 having its ends in continuous open communication with the apex of the V-member a ; the mouth of the groove may be enlarged vertically substantially as indicated at a^2 , Fig. 13, to provide greater range 45 for the entrance of the butts of the short-butt needles. As thus arranged, all the long-butt and medium-butt needles are successively guided upward by the corresponding 50 upwardly inclined side a^3 of the V-opening to the normal knitting level again. The butts of all the short-butt needles, however, instead of being thus guided upward, pass from cam h into groove a^1 , thereby causing 55 the last-named needles to move the respective needle-elevating jacks downward to be acted upon by the jack cam m . Obviously, cam m is in the normal outward position while the jacks are being thus depressed.

The means illustrated and employed for 60 actuating and controlling the movements of cam h for successively deflecting all the needles into the said V-shaped opening a (the cylinder then being in rotary action) may be described as follows: To the periphery of the barrel-cam or drum f , Fig. 1, se-

cured to the intermittently movable shaft s^1 , is fixed a narrow, suitably disposed lug f^1 , and to the rear of said drum is located a tiltingly mounted lever f^3 having its front end arranged in the circular path of and being 70 in normal yielding engagement with the periphery of the drum, and adapted to be actuated by the lug f^1 whenever the latter and said end portion of the lever are in juxtaposition. A link f^4 is connected to the 75 opposite end of the tilting lever and extends upward to the outer end of a horizontal lever lever g , fulcrumed to a bracket f^2 secured to and movable with the cam-plate H . The opposite end of lever g is bent and 80 jointed to the rear portion of a cam-lever h , in turn pivoted to a lateral ear i of the housing of the said instep-cam. The under side of the outer or free end portion of lever h is so shaped and arranged with relation to 85 the needle-butts and V-shaped opening a that the coaction of the lug f^1 , lever f^3 , &c., moves the said free end of lever h downward into the path of the needle-butts, thereby automatically and successively deflecting 90 the needles into the said cam a , as before stated. The thus depressed needles, n^2 , are adapted to produce drop-strokes in the corresponding portion of the web, being the back part of the leg, until they are again 95 elevated to the knitting plane by the jacks. See Figs. 9 and 10, which show the corresponding position of the upper portion of the jacks. Upon moving the said cam-lug f^1 from contact with lever g the reaction 100 of the coil spring p bearing against a collar p^1 , adjustably secured to the said vertical link f^4 , automatically returns the tilting cam lever h to its horizontal or normal position again—see Figs. 1, 14 and 15.

Description of manner of producing the stocking from start to finish.

Assuming the production to be a lady's hose, and also assuming that the various 110 knitting threads are introduced to the needles and knitting-cams as usual, the operation is substantially as follows:

To knit the leg portion.—The needle-cylinder has a series of uniformly spaced vacant or needleless grooves n^4 in one-half, x^1 , of its circumference; all the other grooves of said half carrying long-butt needles n , and having the grooves of the other or opposite semi-circumference, x , filled with short-butt needles n^2 and medium-butt needles n^3 ; the said needles n^2 being diametrically opposite the vacant grooves n^4 . Now, upon normally revolving the cylinder and introducing the thread all the needles are caused to engage the stitch-cams and knit, except the temporarily depressed needles n^2 , these latter being previously deflected into groove a^1 of ring-cam M , and below the stitch-cams by the then tilted cam 120 125 130

or dog h ; cams F , h and m now being in the position shown in Fig. 13; the cam m being outward so as to permit the jacks, forced downward by needles n^2 , to rotate freely 5 past its inner face. The corresponding needle-wave is also indicated in Fig. 13. The continued rotary action of the cylinder, &c., is adapted to produce a continuous open-work web in the leg part down to the commencement of the heel (see Fig. 8) at which instant the speed is reduced and the machine caused to rotate in a reciprocatory manner in a well-known way.

Producing the heel.—The cam m is first 15 positioned to actuate the jacks, as before described, thus moving the short-butt needles n^2 into knitting action, followed by deflecting the long-butt needles n upward out of action; the reciprocatory movement 20 of the cylinder, &c., produces the heel part of the web in the usual manner, see Figs. 9 and 15, the latter figure showing the position of the cams. At the termination of the heel the cylinder is caused to rotate at its 25 normal rate of speed, the cam F dropped to deflect needles n into action, the cam h remaining in the horizontal position with needles n^2 still in action.

In producing the foot part drop-stitches 30 are formed in the upper portion and regular or normal knitting in the sole part. Fig. 10 indicates the corresponding position of the needles when the foot part is being knitted.

35 In knitting the toe portion the needles n^1 , n^2 still continue in action, all the long-butt needles n being moved up out of action by cam F ; the knitting being effected in substantially the same manner as employed in 40 knitting the heel. See also Figs. 9 and 15, cam m being outward.

Upon dropping the stocking from the machine and reintroducing the knitting threads to the needles of the still revolving 45 cylinder the machine is in position to repeat the operation of knitting all-round courses of drop-stitches at the commencement of the next stocking, the production of stockings of this class being successively 50 and automatically continued.

In producing half-hose the operations of knitting the leg, splice, heel, foot and toe are substantially the same as hereinbefore described, except that in half-hose work the 55 machine is stopped after dropping the hose therefrom, while a previously knitted tubular top or cuff mounted on the points or quills of a transfer-ring is temporarily placed on top of the cylinder and over the needles n n^1 , employed in knitting all-round courses of drop-stitches, which are moved upward in the quills, followed by removing the transfer-ring, thereby transferring the loops or stitches of the top to the said needles, and 60 starting the machine; the transference of

top to the leg part of half-hose being a well-known process.

When high-splicing is to be produced in the stocking the all-round drop-stitch knitting ceases at the point where the high splicing begins in the lower portion of the leg part, the cylinder N still continuing in rotary action to produce the desired length of said splicing. Upon changing or introducing the splicing thread the short butt needles 70 n^2 are reinstated into knitting action by the temporarily inwardly positioned cam m , the relation and action of other needles n and n^1 remaining unchanged. At the termination of the said splicing operation, being the 80 commencement of the heel, the cylinder is caused to reciprocate, and the needles n moved upward out of knitting action, the latter being effected by cam F in the usual way, or, as before stated, relatively to the 85 heel production.

It may be explained that in the foregoing description the production of the stocking or web begins at the top of the leg part and terminates at the end of the toe part; the 90 work as knitted passing downward inverted through the cylinder and drops from the underside of the machine.

I claim as my invention:—

1. In an automatic knitting machine provided with a revoluble needle-cylinder, knitting-cams, and means for normally actuating the same, the combination therewith of groups of long, medium and short-butt needles mounted in said cylinder, jacks vertically mounted in the cylinder grooves carrying the short-butt needles, the latter, when idle, normally resting on the upper end of the jacks, a radially movable jack-cam disposed at the base of the cylinder, a main cam-shaft, means for moving said shaft in an intermittent angular manner, and means, actuated by said shaft, for moving said jack-cam into position to be engaged by the jacks in the revolving cylinder, whereby the short-butt needles are moved upward into knitting action.

2. In an automatic knitting-machine of the general character described, provided with a revoluble needle-carrying cylinder having some of its needle-grooves needleless, and devices coöperable with the same adapted to produce longitudinal rows of plain stitches, the combination therewith of suitably disposed jacks mounted in grooves formed in the needle-cylinder, short-butt needles mounted in said jack-carrying grooves and in alinement therewith, a radially movable jack-cam for temporarily elevating the jacks to place said short-butt needles in the normal knitting plane, means for positioning said jack-cam, means for elevating above the knitting plane other or long-butt needles to render them idle, as when the cylinder is reciprocating in pro- 125

ducing the heel and toe parts of a stocking, means for successively moving all the needles downward below the normal knitting plane, and means for elevating all the needles, except the short-butt jack-needles, back to the normal knitting plane.

3. In a drop-stitch knitting-machine of the general character described, the combination of a revoluble knitting-cylinder having mounted in one portion of its circumference a plurality of groups of long-butt needles, each group alternating with one or more needleless grooves, and having mounted in the other portion of the cylinder a plurality of groups of both medium and short-butt needles, the short-butt needles being arranged in the cylinder in grooves diametrically opposite the said needleless grooves, means adapted to coöperate with the medium-butt and long-butt needles to produce a knitted tubular web having drop-stitches in one portion thereof, jacks mounted in the same grooves in which the short-butt needles are placed, means for elevating the jacks to place the short-butt needles upward in knitting action, and means for moving the short-butt needles downward below the knitting plane to render them temporarily inoperative in order to produce corresponding rows of drop-strokes in the back of the leg part of the stocking.

4. In a drop-stitch knitting-machine of the general character described, the combination with a revoluble knitting-cylinder having groups of suitably arranged long, medium and short-butt needles mounted therein, of jacks mounted in the cylinder-grooves in which the said short-butt needles are located, a jack-cam movably positioned at the base of the cylinder, an intermittently movable main cam-shaft, and means actuated by said shaft for changing the position of the jack cam both inward and outward, whereby when moved inward the jacks, upon engaging the cam, are deflected upward to place the short-butt needles in knitting action, and when positioned outward, the jacks are adapted to freely move in the space thus

formed between the outer face of the cylinder and the inner face of the cam.

50

5. In a revoluble needle-cylinder drop-stitch knitting machine of the general character described, the said cylinder having groups of long, medium and short-butt needles and needle-jacks mounted therein, said jacks being disposed in the grooves carrying the short-butt needles, and an intermittently movable main cam-shaft, the combination therewith of a stepped cam fixed to said shaft, and a radially movable jack-cam positioned at the base of the needle-cylinder and actuated and controlled by the stepped cam, whereby, when in use, the jack-cam is caused to be positioned inward at predetermined intervals to deflect the jacks upward, thereby moving the short-butt needles into the knitting plane.

55

60

65

6. In a revoluble needle-cylinder drop-stitch knitting machine of the general character described, the said cylinder having spaced groups of long, medium and short-butt needles and needle-jacks mounted therein, said jacks being disposed in the grooves carrying the short-butt needles, and an intermittently movable main cam-shaft, the combination therewith of a relatively stationary cam-ring disposed above said jacks and encircling the needle-cylinder having an open substantially V-shaped recess formed in its wall, a relatively stationary pivotally mounted deflector-lever located above and adjacent said recess, and means controlled by said main cam-shaft for actuating said deflector-lever, whereby the latter, in co-operation with the revolving needle-cylinder, is caused to be engaged by the butts of all the needles and automatically deflect them downward from the normal knitting level into said V-shaped recess.
